WHEELED PIPE SUPPORT

Charles G. Curtis, El Paso County, Colo.
(Quarters 6602 I, Air Force Academy, Colo. 80912)

Filed Mar. 21, 1967, Ser. No. 6,322

Term of patent 14 years

(Cl. D14—3)

FIGURE 1 is a side elevational view of the pipe support of the present invention. The reverse side is a mirror image of the side shown except for the portions of the wheel braces and chain which would be hidden from view by the wheels.

FIGURE 2 is a front elevational view. The rear elevational view is a mirror image of the view shown.

FIGURE 3 is a top view of the pipe support of the present invention.

The pipe, fragmentarily shown in broken lines, is included only for illustrative purposes.

I claim:

The ornamental design for a wheeled pipe support, as shown and described.
